FRANK E. SEELEY AND GEORGE B. THOMAS, OF BRIDGEPORT, CONNECTICUT. ASSIGNEES TO THE BRYANT ELECTRIC COMPANY, OF BRIDGEPORT, CONNECTICUT, A CORPORATION OF CONNECTICUT.

SHADE-HOLDER.

1,008,081.

Specification of Letters Patent.

Patented Nov. 7, 1911

Application filed May 26, 1911. Serial No. 629,544.

To all whom it may concern:

Be it known that we, FRANK E. SEELEY and GEORGE B. THOMAS, both citizens of the United States of America, and residing at 5 Bridgeport, in the county of Fairfield and State of Connecticut, have invented a certain new and Improved Shade-Holder, of which the following is a specification.

Our invention relates to shade holders and 10 particularly to means for mounting the holder upon its support, the object of our invention being to provide a simple and efficacious device for this purpose which is entirely concealed when the holder is installed.

15 In the accompanying drawings, Figure 1 is a side elevation partially broken away of a shade holder embodying our invention in one form and applied to a lamp socket; Fig. 2 is an inverted plan of the holder showing 20 the ring in place; and Fig. 3 is a perspective of the clamping ring.

The particular globe supporting means carried by the holder form no part of our invention and may be of any desired sort. 25 For convenience of illustration, we have shown a self centering spring wire 5 supported in the depending peripheral skirt 6 of the holder.

To secure the holder to its support, for example to an electric lamp socket, we provide a split clamping ring 7, arranged centrally within the holder. In the holder illustrated this ring is formed independently of the body of the holder and mounted thereon by

35 means of supporting lugs 8, 9 and 10 spaced around the upper edge of the ring, the lug 8 lying substantially opposite the space between the free ends of the ring. A rivet 11 secures the lug 8 beneath the substantially 40 horizontal upper face of the holder, while the lugs 9 and 10 are tangentially slotted at 12 and 13 so that they have limited freedom of angular movement with relation to their supporting rivets 14 and 15. By reason of 45 this limited freedom of movement the ring 7 may be expanded or contracted by means of the clamping bolt 16 and may thus be opened and passed over the usual supporting bead 17, adjacent the lamp receiving end of

50 the lamp socket 18, and then contracted so

as to clamp the holder thereon. To permit of access for a screw driver to the clamping bolt 16, the skirt 6 of the holder is apertured at 19, opposite the head end of the bolt.

Various ways of forming the clamping ring and mounting the same on the holder will readily suggest themselves and we do not limit our invention to the particular method illustrated.

We claim as our invention:—

1. A shade holder having a body part carrying globe supporting means, in combination with a clamping ring and screw therefor both supported within and normally 65 wholly concealed by said holder.

2. A shade holder having a body part carrying globe supporting means, in combination with a clamping ring supported within and normally wholly concealed by said 70 holder, together with a clamping screw concealed within said holder for expanding and contracting said clamping ring, said holder being apertured to permit access to said screw.

3. A shade holder having a substantially horizontal body part, with depending peripheral flange, globe supporting means carried by said flange, in combination with a centrally arranged split clamping ring supported adjacently beneath said horizontal body portion and concealed means for expanding and contracting said ring to grip a support.

4. A shade holder having a substantially 85 horizontal body part, with depending peripheral flange, globe supporting means carried by said flange, in combination with a centrally arranged split clamping ring supported adjacently beneath said horizontal 90 body portion and a concealed clamping screw for expanding and contracting said ring to grip a supporting bead, said peripheral flange being apertured opposite said clamping screw to permit access to the latter.

5. A shade holder having a peripheral depending flange and globe supporting means carried thereby, in combination with an independent clamping ring centrally arranged upon said holder within said flange, the free 100

ends of said ring having tangentially slotted flanges and means in connection therewith for supporting said ring with limited freedom of angular movement upon said holder to permit of the expansion and contraction of said ring to grip a supporting bead.

In testimony whereof we have signed our

names to this specification in the presence of two subscribing witnesses.

FRANK E. SEELEY.
GEORGE B. THOMAS.
